UNITED STATES PATENT OFFICE.

ABNER M. CROTHERS, OF PHILADELPHIA, PENNSYLVANIA.

COIN-DELIVERY MACHINE.

SPECIFICATION forming part of Letters Patent No. 700,306, dated May 20, 1902.

Application filed August 23, 1901. Serial No. 72,998. (No model.)

To all whom it may concern:

Be it known that I, ABNER M. CROTHERS, of Philadelphia, Pennsylvania, have invented a new and useful Improvement in an Attachment to the Chute of a Coin-Delivery Machine; and I hereby declare that the following is a full, clear, and exact description of my device.

My invention is an attachment more particularly adapted to be used on the coin-chute of the coin-delivery machine patented to E. J. Brandt October 2, 1900, No. 658,828; and it consists of a triangular piece of metal having its one side flat and the other side being 15 thickest in the center and sloping thinner toward the edges. The part of the Brandt device to which this attachment is fastened is the coin-chute, which is designated by F in the Letters Patent, the attachment being fastened to F just above the mouth of the coin-chute, as shown in Figures 1 and 2 in the drawings, hereinafter described.

The object of my device is to prevent the lodgment of coins in the chute at its mouth, 25 and this is accomplished by the attachment having its inner side full or thicker in its center part and gradually sloping toward its edges. Thus when a coin is being delivered from each of the two sides of the chute at 30 one time and both coins arrive at the upper part of its mouth at the same time instead of striking each other squarely and locking they are both diverged from their course by means of the sloping sides of the attachment and 35 prevented from locking at the mouth of the chute.

For a more complete description of my device I refer to my drawings hereto attached and made a part hereof.

40 Fig. 1 shows the coin-chute contained in Brandt's device to which my device, design-

nated by numeral 2, is attached, and this figure shows an elevation of the arrangement. Fig. 2 is a view of the chute with my device attached, looking at the chute from its mouth or bottom. Fig. 3 is a side view of the chute. Fig. 4 shows the side of my device which is placed next the chute; and Figs. 5 and 6 are different views of the attachment, showing more plainly its shape.

In the drawings the attachment is designated by numeral 2 and is fastened to the chute by means of screws from the back part of the chute and is fastened directly above the mouth 3 of the chute. The holes 4 and 5 in 45 the back side of the attachment have threads adapted to screws and extend only partially through the attachment, as shown in Fig. 6.

Numerals 6 and 7, 8 and 9, and 10 and 11 are holes in which bolts or screws are placed 50 to fasten the chute to other parts of the machine in which it is used, 13 and 14 being flanges in which the holes 8 and 9 are placed to enable the part to be fastened, as afore- 55 said.

Having fully described my device, what I desire to claim is—

In a coin-delivery machine an attachment to the coin-chute consisting of a triangular piece of metal having its one side flat and 70 its other side thickest in its center and sloping to its edges and fastened to said chute directly above the mouth of said chute, substantially as described and shown.

In testimony whereof I have hereunto 75 signed my name to this specification, in the presence of two witnesses, this 25th of June, 1901.

ABNER M. CROTHERS.
